G. H. ELLIS

PLASTER BOARD AND METHOD OF MAKING SAME

Filed April 2, 1923

INVENTOR.
GEORGE H. ELLIS.
BY HIS ATTORNEY.

James F. Williamson

UNITED STATES PATENT OFFICE.

GEORGE H. ELLIS, OF ST. PAUL, MINNESOTA.

PLASTER BOARD AND METHOD OF MAKING SAME.

Application filed April 2, 1923. Serial No. 629,402.

To all whom it may concern:

Be it known that I, GEORGE H. ELLIS, a citizen of the United States, residing at St. Paul, in the county of Ramsey and State of Minnesota, have invented certain new and useful Improvements in Plaster Board and Methods of Making Same; and I do hereby declare the following to be a full, clear, and exact description of the invention, such as will enable others skilled in the art to which it appertains to make and use the same.

This invention relates to a plaster board and method of making the same. Such boards are now widely used commercially for holding plaster or stucco, both in interior and exterior building construction. The board of the present invention is made of compressed fibrous material and comprises a flat body having plaster holding projections thereon. In the prior art, the body of the board has been formed with depressions of various kinds in which the plaster was supposed to enter so as to be held in position or locked in place.

It is an object of the present invention to provide a board comprising a flat body which has spaced members of comparatively small area projecting therefrom instead of having depressions formed therein.

It is a further object of the invention to provide such a board in which the projections are regularly formed and regularly spaced and are further slightly upset at their outer ends to form a holding means for the plaster.

It is still another object of the invention to provide a method of making such a board whereby the body of the board between the projections will be compressed a greater degree than the body of the board under the projections.

These and other objects and advantages of the invention will be apparent from the following description made in connection with the accompanying drawings in which—

Fig. 1 is a plan view of one form of apparatus used in the process;

Fig. 2 is a central vertical section of Fig. 1;

Fig. 3 is a fragmentary section showing one step of the process;

Fig. 4 is a fragmentary top plan view of the board at an intermediate point in the process;

Fig. 5 is a vertical section taken on the

line 5—5 of Fig. 4, Figs. 3, 4 and 5 being shown on an enlarged scale;

Fig. 6 is a top plan view of the finished board;

Fig. 7 is a top plan view showing one of the uses of the board having a portion thereof broken away; and

Fig. 8 is a vertical section taken on the line 8—8 of Fig. 7 shown on an enlarged scale.

The improved insulated lath board may be commercially made at low cost from various different fibers, such, for example, as cereal straws disintegrated and pulped and preferably reduced approximately to what is known as "half stock." However, it has been found in practice that the board may, in point of cheapness of manufacture and efficiency of product, be made from pulped waste paper, which paper may be easily obtained in large quantities at low cost in practically all countries and especially in the United States.

In using the waste paper, the sulphite and better grades of paper can be sorted and reused to make a high grade paper, while the colored paper may be sorted out and the die stock reclaimed therefrom. By this practice, the salvage obtained in handling the paper will pay for the cost of the same, so that the portion of paper used in making the lathboard costs practically nothing. Waste paper also contains sizing which, to a considerable degree, renders the board made therefrom waterproof. The waste paper is pulped, but need not be, and preferably is not entirely disintegrated. It is, however, reduced to a pulp of such character that it may be molded or pressed to the desired form.

In constructing the board by the present method the same is formed with spaced projections on one surface thereof between which the plaster is adapted to be placed to be held in position thereby. These projections, as shown in Figs. 3 and 6, constitute button-like members extending from one face of the board and have their top or outer surface or portions slightly upset, whereby said members are of greater dimension at their outer portions than at their portion immediately adjacent the body of the board.

One form of apparatus capable of use in the method of making the board is shown in

Figs. 1 and 2. This apparatus comprises a box-shaped mold 1 illustrated as of rectangular form having in its bottom a plurality of spaced apertures or passages. 5 Members 2 are adapted to fit and slide in said passages, which members may be of any desired shape in cross section but which are illustrated as being circular in cross section. The members 2 are provided with convex perforated surfaces facing into the box 1 and said members are also carried by a plate or crosshead 3 slidably mounted on guide members 4 secured to the box 1 and which are illustrated as being in the form 10 of headed bolts, the heads of which limit the movement of the crosshead 3. When the crosshead is in its outermost position, the perforated convex surfaces 5 of the members 2 are disposed in the passages in the box 1 15 at some distance below the bottom of the box. With the members 2 in this position a layer of semi-fluid fibrous material from which the board is made is placed in the mold and a frame 6 which fits the mold is 20 placed thereon, which frame comprises for practically its entire extent of surface, a screen 7. The material is then compressed by pressure exerted between the frame 6 and the bottom of the mold. The water in the 25 material can readily escape through the screen 7 and through the perforated surfaces 5. Owing to the fact that the material is only partly fluid and also due to the fibrous nature thereof, the material between the 30 frame 6 and the imperforate bottom of the mold does not flow outwardly so that the material is evenly distributed, but such portion of the material is compacted to a greater extent than the portion of the material 35 which lies between the frame 6 and the perforated surfaces 5. After the material has been sufficiently compressed, the frame 1 is swung about a shaft 8 carried by the frame 9, which shaft and frame support 40 the mold box 1 to the position indicated in dotted lines in Fig. 2. The frame 1 is provided with a pair of arms 10 carrying lugs at their outer ends through which passes the shaft 8. When the mold is in 45 the position shown in full lines in Fig. 2 it is supported upon an upright wall 11 of the frame 9 and when it is swung to the position shown in dotted lines it is supported upon the lower wall 12. When the 50 mold is in the position indicated by dotted lines, the cross head 3 can be pressed downwardly sliding on the guide rods 4 and the layer of material forming the board will be pressed out of the mold. The form of 55 the board as it is thus taken from the mold is clearly shown in Figs. 4 and 5, one surface of the board has formed thereon a plurality of projecting cylindrical members having concave outer surfaces. The perforations in the surfaces 5 of the members 2

also cause small knobs or projections on the concave outer surface of the projections 13 on the board. With the board in this condition, the same is placed upon a suitable table or platform 14 and passed under a roller 15 illustrated as being carried on a central shaft 16. The roller acting on the top of the projections 13 flattens out the concave surface and upsets the outer end of the projection so that the sides of the members 13 are undercut or said members, in other words, are somewhat T-shaped. The plasterboard is now dried and then ready for use. 70 75

It is thought the use of the board will be obvious from the previous description. The sections of the board will be nailed to the studding or surface of the building to be plastered and the plaster, stucco or similar material will be plastered onto the board 80 between and over the projections 13. With plaster it will only be necessary to cover the surface of the members 13 with a very thin layer of plaster, the main layer of plaster 85 extending between said projections. The use of the board, therefore, effects quite a saving in the volume of plaster used over boards in which the plaster was held in depressions in the surface thereof. Owing to the upset ends of the members 13 the plaster 90 will be interlocked under said ends and thus positively locked and held in position. Considerable difficulty has been experienced with stucco plaster which is commonly used 95 on the exteriors of buildings in getting the stucco into sufficiently close contact with the supporting material. Such stucco is commonly placed on metal lath of various forms. Experiments and investigations on 100 actual pieces of work have shown that only a comparatively small area of the metal lath 105 is efficiently contacted by the stucco. The indentations or spaces formed in metal lath must be sufficiently small to hold the stucco and said lath must also constitute the reinforcing means for the stucco. With applicant's device, a screen of large mesh can be laid over the tops of the members 13 and secured thereto, as shown in Figs. 7 and 8, and will form the reinforcing means for 110 the layer of stucco. The said screen will be held in proper position relative to the said layer by the members 13 and owing to the larger mesh of the screen there will be no difficulty in getting the stucco into the 115 meshes thereof. The stucco will be locked in position by the members 13 between which it will readily enter. A very compact and efficient reinforced layer of stucco is thus 120 formed with the reinforcing medium in the correct position. 125

The board made, as above described, is not only a very good insulator but is quite strong and tough, owing to the fibrous material 130 therein.

After the board has been properly dried the surface containing the projections 13, as well as said projections, may, if desired, be coated or impregnated with any suitable water-proofing material, such as coal tar, varnish, silicates of soda or any other of the known water proofing or fire proofing substances.

From the above description it is seen that applicant has provided a lathboard of great simplicity of efficiency as well as a novel method of producing the same. The body of the board between the projections is quite compact, while the projections themselves have very compact outer portions to form an efficient holding means for the plaster. The high insulating qualities of the board render the same capable of being used both as a sheathing and as a lathing so that the board can be used on the exterior of a building without the wooden or other sheathing usually employed.

It will, of course, be understood, that various changes may be made in the form, composition, details and arrangement of the board structure and in the various steps of the process without departing from the scope of applicant's invention, which, generally stated, consists in a method and product capable of carrying out the objects enumerated and such as shown and described and set forth in the appended claims.

What is claimed is:

1. A plaster board comprising a flat integral body formed throughout of fibrous material having spaced projections extending from one surface thereof, said projec-

tions being spaced from each other in all directions.

2. A plaster board comprising an integral flat body of fibrous material having projecting from one surface thereof regularly spaced button-like members having upset and compressed outer ends.

3. A plaster board formed in one flat integral body of similar fibrous material having spaced upset projections extending from one surface thereof, the portion of the board between the projections being pressed to a greater degree than the portion in and under the projections.

4. The method of making a plaster board which comprises compressing a layer of semifluid fibrous material between a perforated and a partially perforated surface to allow the moisture to escape therefrom, and further compressing the portion contacted by the non-perforated surface to form spaced cylindrical projections within said portion whereby the portion pressed by the non-perforated surface is of greater density.

5. The method of making a plaster board which comprises compressing a layer of semi-fluid substantially homogeneous fibrous material to express the moisture therefrom, compressing a certain area thereof to a greater extent to form spaced cylindrical projections surrounded by said area, forming the ends of said projections with concave outer surfaces, and then compressing the tops of said projections to upset the ends thereof into mushroom shape.

In testimony whereof I affix my signature.
GEORGE H. ELLIS.
